(57) **CLAIM**

The ornamental design for a portable insect repeller and electrostatic device, as shown and described.

DESCRIPTION

FIG. 1 is a front perspective view of a portable insect repeller and electrostatic device incorporating our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left side view thereof, the right side view being a mirror image.

The broken line showing of environment in FIG. 1 is for illustrative purposes only and forms no part of the claimed design.
